United States Patent Office

Des. 195,668
Patented July 16, 1963

195,668

HOLDER FOR MOPS, BROOMS AND THE LIKE

Eldridge W. Thompson, 3212 Yanceyville Road,
Greensboro, N.C.

Filed Dec. 20, 1960, Ser. No. 63,280

Term of patent 3½ years

(Cl. D9—2)

FIG. 1 is a bottom perspective view taken from the front of a holder for mops, brooms and the like, showing my new design;

FIG. 2 is a top perspective view thereof;

FIG. 3 is a sectional view taken along line 3—3 of FIG. 1; and

FIG. 4 is a bottom perspective view thereof from the rear.

The portions shown in broken line are for illustrative purposes only.

I claim:

The ornamental design for a holder for mops, brooms and the like, as shown and described.
